United States Patent Office

Des. 184,889
Patented Apr. 14, 1959

184,889

ROADSTER CAR

William F. Pierson, Canoga Park, Calif., assignor to Alken Corporation, Venice, Calif., a corporation of California

Application September 12, 1958, Serial No. 52,623

Term of patent 14 years

(Cl. D14—3)

Fig. 1 is a side view of a roadster car, showing my new design;

Fig. 2 is a front perspective view thereof; and

Fig. 3 is a rear perspective view thereof.

The dominant features of my design reside in the portions shown in full lines.

I claim:

The ornamental design for a roadster car, substantially as shown and described.
